UNITED STATES PATENT OFFICE.

CHARLES STERN, OF JERSEY CITY, NEW JERSEY, ASSIGNEE, BY MESNE ASSIGNMENTS, TO ARDCO MANUFACTURING COMPANY, OF HOBOKEN, NEW JERSEY, A CORPORATION OF DELAWARE.

AUTOMATIC SAFETY CONTROL FOR TRAIN-LINE AIR BRAKES.

Application filed November 12, 1926. Serial No. 148,055.

The present invention relates to improvements in automatic safety control for train line air brakes, and has for objects to secure the following results:—

5 First: to maintain a uniform application of the brakes throughout the train; also a uniform release of the brakes throughout the train.

Second: to provide for the automatic application of the brakes in case of the accidental or mischievous closing of an angle cock.

Third: to provide means whereby the train line may be charged despite the closed condition of an angle cock therein.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a diagrammatic view showing 25 an automatic safety control for train line air brakes as constructed according to the present invention.

Figure 2 shows a bracket with the control cylinders thereon.

30 Figure 3 is a top plan view of the engineer's valve and partly broken away pipe and valve from main reservoir to the return line.

Figure 4 is a vertical section on an enlarged scale through one of the control cylinders with the valve open, and

Figure 5 is a side view with parts broken away of the fitting for the end of the train.

Referring more particularly to the drawings in Figure 1 a train of three cars is shown, the cars being labeled. The train is provided with the usual train line shown at 26 coupled to the air brake apparatus; and with a return line 27 which is a through line 45 unconnected with the air brake apparatus except that this train line is connected at its rear end by means of the removable fitting 55 to the rear end of the train line 26 and at its front end to the main reservoir 33.

50 The engineer's valve is shown at 11 and the

equalizing reservoir for chamber D pressure at 16. The control cylinders, three in number are shown at 22, 39 and 47.

These cylinders, the reservoir and engineer's valve are all mounted upon the locomotive.

For convenience in construction the three control cylinders may be cast in one with a bracket 60, shown in Figure 2 for convenience in bolting or otherwise affixing the cylinders to the locomotive frame.

In operation, in order to secure uniform application of the brakes the following is the procedure:—

The engineer's brake valve handle 10, is 65 moved to service position, thereby opening up chamber D of the engineer's brake valve indicated generally at 11 to the atmosphere through the preliminary exhaust port 12. The pressure in chamber D, ordinarily main- 70 tained at the train line pressure of 110 pounds or less, as in the case of freight trains, is lowered thus allowing the equalizing piston 13 to move up, because of the greater train line pressure maintained there- 75 beneath, the train line pressure having access to the bottom of the piston through the pipe 14. The movement of the equalizing piston 13 to upper position opens the train line pressure in the engineer's valve 11 to the 80 atmosphere through the exhaust port 15. Chamber D pressure is received from the train line. The equalizing reservoir 16 is connected to chamber D through the pipes 17 and 18, which meet in the cross or four- 85 way coupling 19. The gauge pipe 20 carrying the gauge 21', which shows the train line pressure is connected to the coupling 19 and to this coupling is also connected the pipe 21, whereby the chamber D pressure is 90 also had in the upper end of cylinder 22. In the cylinder 22 below the piston 23 is main- 95 tained the return line pressure, so that when the engineer's valve is moved to the service position, as before stated, and chamber D pressure allowed to fall, this drop in pressure will also be felt in the upper end of cylinder 22, allowing the greater pressure beneath to raise the piston 23 and lift the 100

cylinder which will have the effect to place the lower portion of the cylinder 22 in communication with the atmosphere through the exhaust port 25. This exhaust port 25 is preferably of larger port area than the port area of the exhaust 15 of the engineer's valve, this for the reason that the exhaust pipe 25 evacuates the air from the return line connected with a hose at the end of the 10 train.

The difficulty with the standard system is that when the engineer's brake is applied the train line pressure is evacuated from the front of the train and gradually works 15 its way backwardly, so that there is an initially greater application of the brakes on the first cars. This is undesirable for the reason that it is not uniform causing the cars in the rear to have a tendency to 20 run up on those in front. With the present apparatus the air is evacuated not only from the front of the train through the usual train line 26, but is also at the same time evacuated from the rear of the train 25 through the return line 27, which is connected to the lower end of the cylinder 22 by the branch connections 28 and 29.

In order to secure a uniform release of the brakes, the engineer moves the brake handle 30 to the release position as is customary, and in so doing the brake handle 10 is arranged to strike a crank handle 30 of a valve 31, which is normally kept closed by a coil spring 32 or other device. The valve 31 35 opens the communication from the main reservoir 33 through the pipe 34 to the return line 27. This return line preferably includes a gauge 35 for showing in the engineer's cab the condition of the pressure at 40 the end of the train. It is understood that the return line 27 is a continuous string of piping extending from the front to the rear of the train and for coupling to the rear end of the train line 26, so as to place this 45 rear end of the train line in the same communication with the main reservoir 33 as is had by the front end of the train line. The main reservoir pressure is also circulated by the pipe 36 to the brake valve and 50 to the train line. As a result pressure is led in to the front and rear ends of the train line simultaneously and a uniform pressure is thus had throughout the entire line resulting in the uniform release of the brakes 55 throughout the train. The pipe 34 adjacent the valve 31 may be provided with the cut-out cock 37. This may be closed in case of emergency.

In case any of the angle cocks in the train 60 line should become closed for any reason, or should the train line become stepped-up by hose line jamming or the like, the engineer ordinarily loses control of the train line in rear of this obstruction. In order 65 to take care of this contingency let us as-

sume that the angle cock indicated at X has become closed. In this case the train line pressure will be cut off from this point X rearwardly and the unsupplied rear portion of the train line will gradually leak 70 pressure so that the pressure will fall and this drop in pressure will also be felt in the return line, which is connected through the pipe 38 with the top of the second cylinder 39 having the piston 40 and connected valve 75 41. The lower portion of the cylinder 39 is connected with the extra train line pressure by the branch pipe 42 and the pipe 43 which is coupled to the main train line, as indicated at 44. This extra train line is 80 provided with the cut-out cock 45 to be closed for instance when switching. As the train line pressure behind the closed angle cock X falls, the pressure in the upper portion of the second cylinder 39 falls in like 85 manner and permits the train line pressure below the piston 40 to force the same upwardly and open the valve 41, thus bleeding the train line through the exhaust pipe 46. This will act to apply the brakes on the 90 train in front of the closed or broken angle cock X. At the same time the train line pressure in the upper end of the third cylinder 47, which is coupled to the extra train 95 line 43 falls and permits the pressure in the lower portion of the cylinder 47 to push the piston 48 upwardly thereby opening the connected valve 49 and the exhaust port 50 below it. The lower portion of the cylinder 47 receives train line pressure from the upper 100 portion of the cylinder through the narrow groove 51 in the wall of the cylinder, this groove by-passing the piston 48 in its lower position. The lower portion of the third cylinder 47 also receives the return line 105 pressure through the branch pipe 51 in which is included the check valve 52 permitting flow into the cylinder but preventing back flow into the return line. When the train line pressure falls suddenly in the upper portion of the third cylinder 47 the combined pressures in the lower portion thereof will act to open the valve 49 and permit bleeding of the return line and bleeding of 110 the train line back of the broken or closed angle cock X, thus applying the brakes in the rear portion of the train, as well as in the front portion. The gauge 35 will promptly show the engineer the evacuated condition of the train line behind the closed 115 or broken angle cock X and he will be notified to charge this rear portion. He accomplishes this by opening the valve 31 by hand independently of the brake valve. In opening the valve 31 the pressure from 120 the main reservoir 33 flows into the return line charging the train line from the rear. The engineer can then make an application 125 of the brakes.

The trainman at the rear of the train will 130

carry a detachable coupling having the right and left coupling heads 53 and 54 with the transverse hose 55 therebetween. This coupling will also carry the gauge 56 for showing to the trainman the condition of the pressure at the end of both train and return lines. The tender of the locomotive must also be equipped with one of the right and left couplings but without the gauge 56; this coupling being connected and in use in order to charge the return line as otherwise the brakes on the locomotive and tender would be applied automatically through the first cylinder 22. In case of using the locomotive for switching purposes and in order to place all of the connected cars in the usual condition, as at the present, the cut-out cock 45 may be closed thus cutting out entirely the operation of the improved apparatus 20 and permitting of the switching operations in accordance with the prevailing custom. Of course, it is to be understood that the switching operations may be carried out with the use of the present invention, but it 25 would become necessary to attach and detach the dummy couplings 55 in the rear of each moving train. This would become necessary in coupling and cutting in the return line on all of the cars. The invention will 30 also be found of considerable advantage in connection with very long freight trains. At the present time when the engineer bleeds the line to apply the brakes the reduction in pressure is felt in the forward portion of the 35 very long train, first with the result that the brakes are applied to the forward cars before the brakes in the rear can be applied and the rear cars tend to pile up on those in front damaging the draft gears. Then when 40 the brakes are released, the release takes place also first at the forward part of the train, such forward part having a tendency to run away from the rear part and break the train in two and pull out of the draw- 45 heads. The uniformity of application and release of the brakes had by reason of the present invention, is, therefore, of great value in the operation of long freight trains as the control is had both from the front 50 and rear ends of the train line.

It is obvious that various changes and modifications may be made in the details of construction and design of the above specifically described embodiment of this invention without departing from the spirit thereof, such changes and modifications being restricted only by the scope of the following claims.

What is claimed is:—

- 60 1. An automatic safety control for train line air brakes, comprising in combination with the usual train line, engineer's valve, main reservoir, an equalizing reservoir, a supplemental return line extending to and communicating with the rear portion of the

train line and having controlled communication with the main reservoir, whereby the engineer by actuation of the engineer's valve may simultaneously evacuate and charge the train line from both front and rear. 70

2. An automatic safety control for train line air brakes comprising, in combination with the usual train line, engineer's valve, main reservoir, an equalizing reservoir, a return line extending through the train and 75 in communication at its rear with the rear portion of the train line and connecting at its front with the main reservoir, a valve in the return line biased to a closed position and having an operating member disposed adjacent the engineer's valve for simultaneous operation therewith when the engineer's valve is moved in one direction, and control means for automatically evacuating the rear portion of the train line through said return line when the equalizing reservoir pressure 80 in the engineer's valve falls. 85

3. An automatic safety control for train line air brakes comprising, in combination with the usual train line, engineer's valve, main reservoir, an equalizing reservoir, a return line extending through the train and 85 in communication at its rear with the rear portion of the train line and connecting at its front with the main reservoir, and control means for automatically evacuating the rear portion of the train line through said return line when the equalizing reservoir pressure 90 in the engineer's valve falls. 95

4. An automatic safety control for train line air brakes comprising, in combination with the usual train line, engineer's valve, main reservoir, an equalizing reservoir, a return line extending through the train and in 100 communication at its rear with the rear portion of the train line and connecting at its front with the main reservoir, and a control means comprising a cylinder, a piston therein balanced upon one side by the equalizing reservoir pressure and upon its other side by the return line pressure, and a normally closed valve movably connected with the piston for opening when the equalizing reservoir pressure falls whereby to evacuate the 105 return line. 110

5. An automatic safety control for train line air brakes comprising, in combination with the usual train line, engineer's valve, a main reservoir, a return line through the train in communication with the rear portion 120 of the train line and connected at its forward end to the main reservoir, and control means normally balanced by the return line and train line pressures but adapted to bleed the train line on a reduction in pressure in the return line. 125

6. An automatic safety control for train line air brakes comprising, in combination with the usual train line, engineer's valve, a main reservoir, a return line through the 130

- train in communication with the rear portion of the train line and connected at its forward end to the main reservoir, and control means comprising a cylinder, a piston therein balanced by return line pressure on one side and the train line pressure on the other side, and a normally closed valve coupled for movement to said piston and acting to evacuate the train line when the pressure in the return line falls. 10
7. An automatic safety control for train line air brakes comprising, in combination with the usual train line, engineer's valve, a main reservoir, a return line through the train in communication with the rear portion of the train line and connected at its forward end to the main reservoir, and control means for evacuating the return line following upon the sudden reduction in the train line pressure. 15
8. An automatic safety control for train line air brakes comprising, in combination with the usual train line, engineer's valve, a main reservoir, a return line through the train in communication with the rear portion of the train line and connected at its forward end to the main reservoir, and control means comprising a cylinder, a piston therein balanced at one side by the train line pressure and at the other side by both the train line and return line pressures combined, and a normally closed valve coupled for movement to said piston and adapted to evacuate the return line on a reduction in pressure of the train line. 20
9. An automatic safety control for train line air brakes, comprising in combination with the usual train line, engineer's brake, a main reservoir, an equalizing reservoir, control cylinders, pistons therein, normally closed evacuating valves coupled for movement to the pistons, connections for placing the return line pressure in communication with the valve side of the piston in the first cylinder and with the opposite side of the piston in the second cylinder, a connection for placing the equalizing reservoir pressure against the opposite side of the piston in the first cylinder, and a connection for placing the train line pressure in communication with the valve side of the piston in the second cylinder. 25
10. An automatic safety control for train line air brakes, comprising in combination with the usual train line, engineer's brake, a main reservoir, an equalizing reservoir, means for evacuating the return line pressure normally closed and balanced by the return line pressure on one side and the equalizing reservoir pressure on the opposite side, and means for evacuating the train line pressure normally closed and balanced by the train line pressure on one side and the return line pressure on the other side. 30
11. An automatic safety control for train line air brakes, comprising in combination with the usual train line, engineer's brake, a main reservoir, an equalizing reservoir, means for evacuating the return line pressure either upon a falling equalizing reservoir pressure or a fall in the train line pressure. 35
12. An automatic safety control for train line air brakes, comprising in combination with the usual train line, engineer's brake, a main reservoir, an equalizing reservoir, a first control means, movable evacuating means therein balanced on one side by the return line pressure and for evacuating the train line pressure and balanced upon its other side by the equalizing reservoir pressure, and other control means having movable evacuating means therein balanced on one side by the return line pressure and for evacuating the return line pressure and balanced upon its other side by the train line pressure. 40
13. An automatic safety control for train line air brakes, comprising in combination with the usual train line, engineer's brake, a main reservoir, an equalizing reservoir, a first control cylinder, balanced valve evacuating means therein accessible on its valved side to the return line pressure and on its opposite side to the equalizing reservoir pressure, a second cylinder having movable valved and balanced evacuating means therein accessible on its valved side to the train line pressure and on its opposite side to the return line pressure, and a third control cylinder having movable balanced valved evacuating means therein accessible on the valved side to the return line pressure and train line pressure combined and on its opposite side to the train line pressure. 45
14. An automatic safety control for train line air brakes comprising, in combination with the usual train line, engineer's valve, a main reservoir, a return line extending the length of the train and connected at its front end to the main reservoir, and a detachable coupling fitting having coupling heads for engaging the couplings on both the return and train lines for establishing inter-communication between the same at the rear portion of the train. 50
15. An automatic safety control for train line air brakes comprising, in combination with the usual train line, engineer's valve, a main reservoir, a return line extending the length of the train and connected at its front end to the main reservoir, a detachable coupling fitting having coupling heads for engaging the couplings on both the return and train lines for establishing inter-communication between the same at the rear portion of the train, and a gauge carried by the coupling for showing the pressure condition at the end of the train. 55

16. An automatic safety control for train line air brakes comprising the usual train line, engineer's valve, main reservoir, an equalizing reservoir, a return line extending the length of the train, a detachable fitting for placing the rear ends of the train line and return line in communication, said return line being in communication with the main reservoir, a gauge for showing to

the engineer the train line pressure, a juxtaposed gauge for the return line pressure, and a valve in the return line accessible for independent manipulation by the engineer and positioned for simultaneous movement with the engineer's valve in one position of the latter.

In testimony whereof I affix my signature.
CHARLES STERN.
